[57] CLAIM

The ornamental design for a combined door and panel for an enclosure, as shown and described.

DESCRIPTION

FIG. 1 is a top plan view of the combined door and panel for an enclosure;

FIG. 2 is a front elevational view thereof;

FIG. 3 is a right side elevational view thereof;

FIG. 4 is a bottom plan view thereof;

FIG. 5 is a rear elevational view thereof;

FIG. 6 is a left side elevational view thereof;

FIG. 7 is a rear elevational view of a second embodiment of a combined door and panel for an enclosure. The front, right and left sides, top and bottom are the same as those views of the combined door and panel for an enclosure in the first embodiment; and,

FIG. 8 is a bottom plan view of the third embodiment of a combined door and panel for an enclosure. The front, rear, top, left and right sides, are the same as those views of the combined door and panel for an enclosure in the first embodiment.
